UNITED STATES PATENT OFFICE

2,630,500

ELECTRIC CONTACT MAKING DEVICE

Frederick E. Rommel, West Dulwich, London, England, assignor to Telephone Manufacturing Company Limited, London, England, a British company

Application November 29, 1950, Serial No. 198,061
In Great Britain December 8, 1949

7 Claims. (Cl. 200—1)

1

This invention relates to electric contact making devices of the type such as is widely used in telecommunication apparatus and including a plurality of fixed, spaced, aligned and substantially parallel contact carrying members, adapted to cooperate with a plurality of aligned spaced contact carrying members movable in the direction of alignment to make or break connections between the contacts carried by the respective members.

Much attention has been directed to the design of the contact carrying members for electromagnetic relays of this type having multiple contact sets, "contact set" being used here in the sense of that group of contacts between which connection is made or broken in the operation of the relay. In relays at present in wide use, the contacts are carried at the ends of parallel flat spring members usually referred to as springs, the moving contacts being carried by springs intermediate the fixed contacts. In order to secure reliability and uniformity of performance of relays of this type, particularly for telephone apparatus, it is necessary for the spring pressures to be accurately adjusted and such adjustment is a slow, tedious and costly operation in the production of the relays.

The present invention has for its object to provide an improved form of relay of the type referred to and in which multiple contact sets are used, and wherein individual adjustment of the contact carrying members can be assisted by mechanical means, in contrast to the conventional arrangement where manual adjustment is largely necessary. The invention also has for its object to provide an improved method of manufacturing electrical contact making devices of this kind.

The present invention consists of an electric contact-making device of the type referred to, comprising means for securing and spacing the fixed contact carrying members independently of the moving contact carrying members, whereby the latter can be assembled without affecting the spacing of the fixed contacts and means for maintaining substantially constant the spacing of the moving contacts.

The invention further includes an electric contact-making device of the type referred to comprising means for supporting said fixed contact carrying members in parallel spaced relationship, and means for supporting said moving contacts independently of said first supporting means, and insulating means for maintaining substantially constant the separation of said moving contacts.

At the present time it is the practice to make

2

relays and electromagnetically operated switches for telecommunication purposes with contact springs which are arranged in a stack or "pile" and are clamped each at one end with interposed insulating spacers. The springs are arranged usually with alternate moving and fixed contact springs, though the "fixed" springs are, of course, resilient. The fixed springs are arranged to rest each on a buffer, or stop, and the moving springs rest on an insulating actuating member coupled to the armature of the relay.

Thus, a considerable number of individual pairs of contacts have to be operated simultaneously by the armature of an electromagnet. As the electric power and the space available for the complete switching device is in practice limited, the mechanical pressure and the armature travel available for operating the contacts needs to be reduced to the lowest figure compatible with reliable operation. Experience shows that, with economical production methods, contact clearances in the order of .010" to .015" and a complete armature travel in the order of .030" to .040" are necessary to ensure reliable operation. These relatively small values and the necessity of ensuring an adequate minimum contact pressure have, in the past, led to the development of the buffered spring set which is now almost universally adopted for these switching devices.

A buffered spring set will thus include a spring (the "buffer spring") clamped between spacers in a spring pile and tensioned against the buffer, and a moving spring constituting the second contact carrier, clamped between spacers in the same spring pile and tensioned against a lifting pin operated by the armature. The adjustment of the springs of such a spring set include three operations, which have to be made by hand:—

(i) Tension buffer spring against buffer to value required to ensure contact pressure.

(ii) Tension moving spring against lifting pin, and

(iii) Bend spring tips to obtain correct contact clearance.

These three adjustments need to be made with in narrow limits in order to ensure a minimum contact clearance in the non-operated position and a minimum contact pressure in the operated position with a given armature travel. Contacts mounted, adjusted and operated in this way have proved to be highly efficient and reliable. Their main disadvantage is the cost of carrying out, by hand, the adjustments described above, and attempts to eliminate all or part of the manual adjusting operations by pre-stressing the springs

before assembling have not proved satisfactory. As a result, electromagnetic switching devices with a large number of contact pairs, such as cross bar switches, selective relay units and so on involve a high degree of manual adjustment, which has a considerable influence on their manufacturing cost.

In order to reduce this cost, a simplified type of contact system has been suggested in the past for cross-bar switches. In this arrangement a moving spring forming one contact carrier, is clamped between insulating spacers and tensioned against a driving pin. The second contact is mounted on a rigid bar which forms the second contact carrier and is fixed rigidly relative to the clamping spacers. Whereas in the conventional spring set described, the contact pressure is ensured by lifting the buffer spring off its buffer, in this case the contact pressure would be obtained by flexing the moving spring against the rigid bar. The necessary contact adjustments are reduced to:

- (i) Tension moving spring against lifting pin.
- (ii) Bend moving spring tip to obtain correct contact clearance.

These adjustments also need to be within narrow limits, and as the adjustments are not independent they are not so easily made as with the buffer spring described.

The present invention is concerned with overcoming much of the time and expense of adjusting relay contact carriers, and various ways of carrying the invention into effect will be described with reference to the accompanying drawings in which:

Figure 1 is a side elevation of a selective relay unit, partly in section.

Figure 2 is a front elevation of the same unit.

Figure 3 is a plan view of the contact arrangement of the unit, and

Figures 4 and 5 are diagrams indicating modified forms of contacts.

This embodiment of the invention is a selective relay unit, of the type having a series of electromagnets, each with associated sets of contacts, and a main operating magnet; when one of the series of electromagnets is operated no contacts of the various sets are actuated, but operation of the main electromagnet causes to be operated only those contacts associated with the energised electromagnet. It is convenient to refer to the electromagnets of the series as the finger magnets.

This relay unit comprises an open box frame 10 within which are located finger magnets 11, in this case five in number. The finger magnets are secured to a magnetic support plate 12, fastened in the frame 10 by screws 13, connecting tags 14 for the magnets pass through the plate. The magnets have armatures 15 which carry spring fingers 16 having at their free ends lugs 16a and 16b formed thereon and bent respectively downwardly and upwardly. The operation of a finger magnet causes the armature to be drawn rearwardly into the position of the rear-most finger shown in Figure 1. Thus no contacts are operated by this movement, but lugs 16a are brought into the position in which they serve to couple movement from a main magnet to the contacts to be actuated.

The main magnet closely resembles a type adapted as standard in relays used by the British Post Office and comprises a magnetic frame 17, coil 18 and armature 19. The armature is adjustably spring loaded by a helical spring 20;

5 the fittings of the magnet are so well known as not to warrant further description, except that the pivoted armature carries a support member 21 for an operating bar 22 which lies below and adjacent the lugs on the fingers 16.

10 The main contact assembly of the relay unit is disposed above, and is secured to the box frame 10. This assembly includes a base plate 23 secured to the frame by screws 24; the base plate, and the parts, including the contact-carrying members, which form part of the contact assembly can be detached as a sub-unit from the box frame.

15 The contact assembly includes contact-carrying springs arranged in five vertical banks, disposed one above each finger magnet armature, and associated with that armature. Each bank includes fixed contact carrying springs 25 alternating with moving contact carrying springs 26. The fixed springs are clamped between spacers 27 formed of strips of insulating material, the spacers being secured by bolts 28. The free length of the fixed springs, extending from the stack of spacers is short, being less than one inch, and preferably of the order of half an inch.

20 The moving contact carrying springs are likewise mounted at one end in the stack of spacers 27, but are not clamped therein, and are held in a manner to be described hereinafter. The moving springs 26 are shown as being of approximately the same length as the fixed springs but may be slightly longer.

25 The contacts on the springs are formed by suitably shaping the ends, and by coating these parts with an appropriate metal.

30 The contact ends of the moving springs of each bank are spaced from each other by engaging and being located in one of five insulating members 29. These are formed each of a thin strip 40 of sheet insulating material which is stamped with a series of thin transverse slots 29a along its one edge into which fit the ends of the moving springs of one bank. The insulating strip is guided for movement vertically by means of two slotted guide plates 30 and 31 secured one 45 to the top of the stack of insulating spacers 27 and the other to base plate 23. Conveniently, the slots in the two plates are open ended, as shown in Figure 3 to facilitate assembly. The downward movement of each strip in the slotted plates is limited by a shoulder 29b formed on the strip and adapted to engage the lower plate 31. The bottom ends of each of the strips 29 are adapted 50 to rest between the lugs 16b on the appropriate armature finger 16. When, therefore, the appropriate finger magnet is energised the armature will have moved the lugs 16a to the position over the operating bar 22, and on subsequent operation of the main magnet the bar will rise 55 and lift the insulating strip 29. The moving contacts are thereby moved.

60 In adjusting the contacts of this assembly it is necessary to make one adjustment only, namely to bend the fixed springs until they are accurately spaced from each other and from some datum, 65 for example the surface of base plate 23. It is not necessary to set up the moving springs either as to pressure or as to separation for the reason that each spring, very near the contact, is located 70 by the slots 29a in the strip 29. It is, of course, a relatively simple matter to manufacture the strips with a very high uniformity from one to the next, and by this means a corresponding high degree of uniformity of spacing of the moving contacts can be obtained. It is necessary for the 75

springs to fit with a working clearance in the slots, but this can easily be made smaller than the tolerance in the desired spacing between fixed and moving springs.

With the arrangement described the moving springs can be made as thin and light as desired, since the springs are relieved of the duty of locating the contacts as in the usual arrangement and serve only to carry the contacts and the electric current to them.

It is advantageous to provide double contacts on the carriers and the construction described lends itself particularly well to this. Thus the moving contact carriers can be made as shown in Figure 3, each with a central stem portion 26a which is relatively thin and narrow, an enlarged end portion 26c by which the spring is positioned in the stack of insulating spacers and an enlarged contact carrying end 26b. The latter end is then forked, by slotting the enlarged portion and the insulating strip 29 can then be located within the fork, with one arm of the fork on each side. Each arm is transversely corrugated at its ends to provide contact making portions.

The fixed contact springs are similarly made double to pass each side of the insulating strip and to engage the double moving contacts, but in this case each spring is slotted back to the clamping point so as to provide two virtually independent arms. Such independent arms can more easily accommodate themselves to small variations of dimensions of the moving contacts than can the comparatively short arms on the ends of a conventional twinned spring.

In spring sets of this type for cross bar switches in a selective relay unit for a cross bar system rows of springs may be connected together, it is then possible, with the construction described to make the fixed contact springs as a single member. This member is stamped from a metal sheet and is shaped so that extending from the clamping line are pairs of independent springs as indicated at 25 in Figure 3. Sufficient space is provided between each pair of springs to accommodate the width of the insulating strip 29 operating the contacts so that the contacts proper remain visible for inspection from the front of the spring set when the final assembly is completed.

The spring tips may be provided with contacts in the conventional manner, or, in order to further facilitate the automatic adjustment and to reduce production cost, the complete row of springs may be blanked in one operation out of a strip of spring material with a suitable thickness of appropriate contact metal rolled on to the part which will form the spring tips, thus providing a surface of contact metal on the tips. The overall thickness of the springs is the same at the contacted surfaces as on the rest of the length and this facilitates automatic adjusting.

The rigid contact springs may also be provided with contacts in the conventional way, or may embody locally rolled on contact metal as in the case of the springs. In the latter case, in order to provide a definite position of the contact, the contact carrier may be suitably corrugated as shown or may have raised pins embossed into it. This latter operation may be performed in a manner suitable to increase the effective thickness of the contact metal locally at the position of the contact.

The springs may, of course, be embossed in a similar manner to provide counter contacts if desired.

Despite the fact that with the construction

described it is necessary to adjust only the fixed contact springs, the adjustment of such springs in the completed unit would nevertheless be difficult owing to inaccessibility. It is an important feature of the present invention that the fixed contact springs can be assembled and clamped before the moving springs are inserted in position between them. This is of great practical importance, since it is not a difficult matter to design an apparatus for straightening or adjusting only the fixed springs when there is no obstruction by the moving springs and this is particularly so with the present construction since accurate spacing only of the springs is required.

The method by which the moving springs are carried is indicated in Figure 3. At the rear end of each moving spring is formed an enlargement 26c and this serves as a stop to limit the movement of the spring in a slot formed in the spacers 27 to receive it.

The forward end of each moving spring is of course retained by the insulating strip 29 so that the spring is therefore securely held in the completed unit. In assembling the unit, therefore, the fixed springs are assembled clamped and adjusted; this adjustment is effected by bending the springs in alternate directions, to a decreasing extent each time. The moving springs are then dropped into the slots in the spacers provided to receive them, without any release of the now adjusted fixed springs. The insulating strips are inserted, and held in position by the slotted plates 30 and 31.

A separate restoring spring operating against the insulating strips may be provided, but in the case where numerous springs are used the sum of the pressures exerted by the individual contact springs may be sufficient to provide the necessary restoring force. This measure still does not constitute a reversion to the old lever spring principle as no individual adjustment of springs is involved and one or more of the moving springs may even rest on the upper edge of the slot in the insulating strip without detriment to the proper operation of the spring set.

In a spring set with "make" contacts built up in this manner, the operating pressure to be provided by the armature is equal to the sum of all contact pressures plus the restoring pressure. It is, of course, desirable to keep the latter as low as possible and, it is for this reason, that the cross section of the flexing length of the connector strips is kept as low as possible with due regard to mechanical stability, and the length of this portion of the connector as great as possible. At the same time, since there is no need to clamp the moving springs it is not difficult to achieve a low restoring force, even with multiple springs. It will be seen also that with the slotted mounted arrangement for the moving spring the flexing length is increased.

The fixed springs are kept short, as is pointed out above. This has the obvious merit of compactness, but in addition this reduces variations in the position of the contact tips owing to small movements in the clamping edges of spacers, which may be caused by pressure changes resulting from alteration of temperature or humidity. As the springs can now be automatically adjusted in toto by means of a tool, considerations of accessibility no longer apply and the length of the spring can be reduced to a value determined only by production and contact pressure considerations, and the figure of half an inch becomes practicable. This comparative shortness

of the spring relative to the contact travel also increases the rubbing which occurs and thus the self-cleaning properties of the contacts are improved.

In a modified form of contact spring shown in Figure 4 the fixed springs are located in a stack of insulating spacers, as described above, but the moving springs each take the form of a wire 32. The end of the wire is bent at right angles and is passed through the insulating strip 29 which is guided for vertical movement as before. The other ends of the wires pass freely through openings in the stack of insulating spacers and project behind the stack to provide connecting lugs at 32a. With this construction also it will be seen that the adjustment of the fixed springs only is required, the spacing of the moving springs being determined permanently by the ends of the wires secured in the insulating strip.

In a modification of the arrangement described, the moving spring can be dispensed with as such, the moving contacts being rigidly supported upon an insulating member. Such an arrangement is shown diagrammatically in Figure 5; here the fixed contact springs 25 are clamped in the pile of spacers 27, but moving contacts 33 of a relatively short and rigid construction are secured to the insulating strip 29. The strip 29 is actuated as described above. Connection is made to the contacts 33 by any light conductors, such as thin foil connections 34. The foil connections may be supported in the stack of spacers 27, or in a separate stack, and with a relay unit for a cross bar system, instead of connecting the fixed contacts together, the moving contacts of the various banks can be joined by light foil connections.

I claim:

1. An electric contact making device comprising the combination with a plurality of fixed contact carrying members and a cooperating plurality of movable contact carrying members; of insulating spacer means notched to provide a plurality of slots for receiving the respective fixed contact carrying members to support and space the same independently of the movable contact carrying members, whereby the latter can be assembled without affecting the spacing of the fixed contacts, means comprising a bar of insulating material supporting the contact carrying ends of said movable contact carrying members and maintaining the spacing of the contacts thereon substantially constant, and means including said bar for retaining said movable contact carrying members with portions thereof seated in said slots and in interleaved relation to the fixed contact carrying members.

2. An electric contact making device comprising a series of substantially parallel fixed spring

members, contacts on said fixed members, spacers of insulating material between said fixed members adjacent the ends thereof, clamping means for clamping said fixed members and said spacers to hold said fixed members in spaced substantially parallel relationship, a series of movable contact carrying members, contacts on said movable members, insulating spacing means for maintaining substantially constant the separation of the contacts on said movable members, and means including said spacers and said insulating spacing means for removably supporting said movable contact carrying members in cooperative relation to said fixed members, said spacers when assembled with said fixed members providing slots for the entrance or removal of said movable members.

3. A device according to claim 2 wherein said insulating spacing means are recessed to receive the ends of moving contact carrying members.

4. A device according to claim 2, wherein said movable contact carrying members comprise wires, and said insulating spacing means comprises a bar of insulating material having openings therethrough through which the ends of the said wires pass.

5. A device according to claim 2, and comprising, as a part of said means removably supporting said movable contact carrying members, means guiding said insulating spacing means for linear movement; said movable contact carrying members being seated in recesses in said insulating spacer means, said movable members being thereby held against removal from said recesses and from said slots of said assembled spacers.

6. A device according to claim 2 wherein the said fixed contact carrying members are supported near one end thereof and the free contact carrying part thereof is not greater than one inch in length.

7. A device according to claim 6 wherein said part is of the order of one half of an inch in length.
